CLAIM

We claim the ornamental design for a presentation cradle, as shown and described.

DESCRIPTION

FIG. 1 is a first perspective view of a presentation cradle;

FIG. 2 is a second perspective view thereof;

FIG. 3 is a bottom view thereof;

FIG. 4 is a top view thereof;

FIG. 5 is a first side view thereof;

FIG. 6 is a second side view thereof;

FIG. 7 is a front view thereof; and,

FIG. 8 is a rear view thereof.

The broken lines depict portions of the article that form no part of the claimed design.

1 Claim, 8 Drawing Sheets
